VIBRATORY ROTARY DEVICE

Terrence J. Schumacher, Grayslake, Ill.

Application July 24, 1946, Serial No. 685,930

3 Claims. (Cl. 46—47)

1

This invention relates, in general, to a vibratory rotary device, and has particular relation to an electrically operated device rotated by vibration and adapted for use with model airplanes, or as a toy, although not limited to such use.

One of the main objects of the present invention is to provide a device having a vibratory member adapted to be vibrated by an electromagnet, and in which a propeller or other rotary member is adapted to be rotated by vibration of said vibratory member.

Another object of the invention is to provide in a device of the character described, means for reversing the direction of rotation of the rotary member; more particularly, a mounting for the vibratory member, which mounting is adapted to be manipulated to reverse the angularity of the vibratory member relative to the pole end of the electromagnet whereby to reverse the direction of rotation of the rotary member.

Another object of the invention is to provide a device of the character described having various features of novelty and advantages, and which is particularly characterized by its simplicity in construction, its lightness in weight, its economy in manufacture, its adaptability for use for rotating the propeller of a model airplane or the like, or as a toy, and its effectiveness in use for the purposes set forth.

Further objects and advantages of the invention will appear from the following detailed description, taken in connection with the accompanying drawing in which:

Figure 1 is a side elevation and more or less diagrammatic view of a device embodying the present invention;

Figure 2 is a top plan view of the device shown in Figure 1; and

Figure 3 is a detail section taken on the line 3—3 of Figure 1.

Referring now in detail to the drawing, the device shown in Figures 1, 2, and 3 comprises an angular bracket 1 formed, for example, of iron or steel and having an integral outturned or lateral lug 2 on the leg 1a thereof. An electromagnet 3, suitably mounted at 4 on the other leg 1b of the bracket 1, comprises a coil 5 and a core 6.

The armature is in the form of a flat spring strip 7 secured to the lug 2, for example, by bending integral side projections 8 on the lug 2 over and into firm holding engagement with the adjacent end of the strip 7. The strip 7 extends adjacent the pole end of the electromagnet 3 to be vibrated by energization of the electromagnet, with the width of the strip 7 presented at an

2

angle to the pole end of the electromagnet 3 as shown in detail in Figure 3.

The rotary member 9 is in the form of a propeller for use, for example, as the propeller of a small model airplane, or the propeller may be used as a toy or otherwise as desired. An escutcheon pin 10 loosely couples the propeller 9 to the adjacent end of the strip 7, whereby the propeller 9 is rotated about the pin 10 by vibration of the strip 7 when the electromagnet 3 is energized. The pin 10 is shown as headed at its free end at 11. The shank of the pin 10 passes loosely through a hole 12 at the axis of the propeller 9, and the pin 10 is secured to the adjacent end of the strip 7, for example, by soldering, as at 13.

The coil 5 of the electromagnet 3 is connected in circuit with a bell type transformer 14 by conductors 15. The transformer 14 has conductor means 16 provided with suitable connector means 17 for connecting the transformer in circuit, for example, with a 110-volt A.-C. outlet, or with a battery or other suitable source of current.

A current interrupter 18 has cooperating contact arms 19 and 20 connected into the circuit between the transformer 14 and the coil 5 of the electromagnet 3. One contact arm 19 is secured to the lug 2, for example, with the attachment of the flat spring strip 7 thereto, and the other arm 20 may be secured to the adjacent leg 1a of the bracket 1. The circuit between the bell type transformer 14 and the coil 5 is through one conductor 15 to binding post 22, from the post 22 to the arm 20, and thence through the arm 19 and coil 4 to the other conductor 15 and to the transformer 14.

In use, when the coil 4 of the electromagnet 3 is energized by closing the circuit, the strip 7 is vibrated and the vibration of the strip 7 rotates the vibratory member or propeller 9 through the loose coupling 10 between the member 9 and the strip 7. The angularity of the strip 7 relative to the pole end of the electromagnet 3 determines the direction of rotation of the propeller 9.

The lug 2 is adapted to be engaged between the fingers, or by a suitable tool, and twisted to reverse the angularity of the strip 7 relative to the pole end of the electromagnet 3. Then when the electromagnet 3 is energized with the angularity of the strip 7 thus reversed, the propeller 9 will be rotated in the opposite direction by vibration of the strip 7. Other means for adjusting the direction of rotation of the propeller 9 are contemplated within the scope of the present invention. The strip 7 is shown in dotted lines

in Figure 3 in position of reverse angularity, as above described.

The embodiment of the invention shown in the drawing is for illustrative purposes only, and it is to be expressly understood that said drawing and the accompanying specification are not to be construed as a definition of the limits or scope of the invention, reference being had to the appended claims for that purpose.

I claim:

1. In a device of the class described, in combination, an electromagnet having a core, a support, a vibratory member adapted to be vibrated by said electromagnet and comprising a flat, narrow magnetic spring strip mounted at one end on said support and extending in nearby spaced relation across the end of said core and at substantially right angles to the axis of said core, said spring strip having its width presented at an acute angle to the adjacent end of said core, a pin carried by and projecting endwise from the free end of said strip, and a rotary member loosely mounted at its axis on said pin for rotation thereon in a plane at substantially right angles to the direction in which said strip extends, the angularity of said strip relative to the

adjacent end of said core causing rotation of said rotary member on said pin when said strip is vibrated by said electromagnet.

2. A device according to claim 1 wherein the mounted end of said spring strip is supported for rotation of the strip about its longitudinal axis whereby to reverse the acute angle which the width of the strip presents to the adjacent end of the core of the electromagnet.

3. A device according to claim 1 wherein the electromagnet has a coil provided with an electric circuit and wherein there is a circuit interrupter in said circuit.

TERRENCE J. SCHUMACHER.
